(57) **CLAIM**

The ornamental design for a holder, as shown and described.

DESCRIPTION

FIG. 1 is a front perspective view of the holder showing my new design.

FIG. 2 is a front view of the holder of FIG. 1.

FIG. 3 is a rear view of the holder of FIG. 1.

FIG. 4 is a right side view of the holder of FIG. 1.

FIG. 5 is a left side view of the holder of FIG. 1.

FIG. 6 is a top view of the holder of FIG. 1; and,

FIG. 7 is a bottom view of the holder of FIG. 1.

The broken line showing of stitching is included for the purpose of illustrating structural environment and forms no part of the claimed design.
